(57) **CLAIM**

The ornamental design for a part of cut-off valve as shown and described.

DESCRIPTION

1. Part of cut-off valve

1.1 : Front

1.2 : Back

1.3 : Left

1.4 : Right

1.5 : Top

1.6 : Bottom

1.7 : Perspective

1.8 : Perspective

1.1 is a front plan view of a part of cut-off valve showing my new design; 1.2 is a back plan view thereof; 1.3 is a left side elevational view thereof; 1.4 is a right side elevational view thereof; 1.5 is a top elevational view thereof; 1.6 is a bottom elevational view thereof; 1.7 is a right, front, top perspective view thereof; and 1.8 is a left, rear, bottom perspective view thereof; The broken lines in the drawings depict portions of the part of cut-off valve that form no part of the claimed design.
